[57] **CLAIM**

The ornamental design for a toy crane element, as
shown and described.

DESCRIPTION

FIG. 1 is a top perspective view of a toy crane element,
showing my new design;

FIG. 2 is a bottom perspective view thereof;

FIG. 3 is a front elevational view thereof;

FIG. 4 is a rear elevational view thereof;

FIG. 5 is a top plan view thereof;

FIG. 6 is a bottom plan view thereof; and

FIG. 7 is a side elevational view thereof, the opposite
side being a mirror image.

FIG.7

FIG.3

FIG.5

FIG.4

FIG.6
